UNITED STATES PATENT OFFICE

CARL ROEHRICH, OF BERLIN, GERMANY, ASSIGNOR TO THE FIRM SILFREE AKTIEN-
GESELLSCHAFT, SILFREE LIMITED, OF VADUZ, GERMANY

METHOD OF TREATING PHOTO-SENSITIVE BODIES

No Drawing. Application filed December 23, 1929, Serial No. 416,204, and in Germany April 23, 1929.

This invention is concerned with the production of photographic films or plates and particularly with improvements over the methods disclosed in my copending application, Serial No. 337,738, filed February 5, 1929.

The above mentioned original application has to do with an improved and simplified copying method, and those parts of this 10 parent case, which are thought to be essential for an understanding of the present invention, will be verbally incorporated in the explanations and descriptions which are to follow:

15 The usual procedure in producing films and the like consists in first making a negative in any well known manner and in then copying this negative on a suitable transparent film, provided with a photosensitized 20 layer.

This layer may be a silver-free colloid, sensitized by chromic acid salts. During the copying under the negative, the light rays striking the colloid layer will cause a hardening of the concerned sections to a certain 25 depth. The quality of the film or plate depends largely on the uniformity of the hardened sections or on the completeness of 30 hardening. To explain this a little more in detail, it is essential that the hardening is uniform throughout the entire section and complete as to its thickness.

As has been said above, the copying under 35 the negative produces partially hardened sections under ordinary conditions of exposure. Now, the further treatment of the films or plates may be performed in various ways, but it always produces difficulties on account of the incompleteness of the hardening. For 40 example, dyes may be used for coloring the non-hardened parts. The coloring liquid is absorbed by the non-hardened parts, and, since the adjoining hardened sections are only hardened to a certain depth, the coloring 45 liquid may, similarly to the first case, enter underneath the hardened parts and produce dimmed pictures. On the other hand, if mordants are used for coloring the hardened 50 sections, the results will be undefined colors, because the hardened section is incomplete as

to thickness of the colloid layers. Therefore the colors will be poor and fading.

Complete and uniform hardening of the concerned sections may be accomplished by long exposure or by storing in a moist atmosphere. However, these possibilities harbour serious difficulties in view of the expense incident to their realization, e. g., the element of time introduced in both cases makes either case exceedingly costly. Furthermore the 55 application of the above mentioned storage treatment in a moist atmosphere presents appreciable difficulties in case of long films which can not be conveniently kept for any length of time.

The object of the invention disclosed in the copending application is to produce quality films or plates, and to overcome the handicaps of previous methods intimated above, in novel and more expedient ways, particularly 60 as explained below.

Up to the moment of copying the negative, the previously known methods and the improvement disclosed in the copending application run parallel. The difference appears in the manner in which uniformity and completeness are attained. While others have tried to reach this aim by the costly and time-consuming procedure of long exposure and storing in a moist atmosphere, the method proposed in the copending application aims to attain uniformity and completeness 65 of hardening inexpensively and quickly.

After the first exposure, which produces hardened and unhardened sections on the film or plate, the unhardened sections are subjected to a treatment so as to prevent the possibility of changing their consistency under the subsequent influence of light rays. This may be done in various ways and is preferably effected by simple moistening in a moist atmosphere, by applying moisture by means of rollers, by spraying or washing, or in any other suitable manner. The film or plate may then be directly exposed to the action of light rays for a short period of time.

The principles underlying the method disclosed above are as follows. Moistening, generally speaking, effects the sensitivity to

light of the colloid layer. Since the non-hardened parts absorb moisture quickly, it is evident that the sensitivity of these parts will be greatly effected, while the hardened parts will remain relatively unaltered because of comparatively little absorption of moisture. Now, by re-exposing the colloid layer at this time to the direct action of light rays, the previously hardened parts having retained sensitivity, will again benefit by the exposure. Uniformity of hardening is thereby effected and completeness as to depth will be reached because the section, which at the time of the first exposure was only partially hardened, will now be hardened completely.

Referring to the difficulties experienced with previous methods, and particularly to the coloring of the films, as intimated previously, it will be remembered that the coloring liquid might have entered underneath the partially hardened sections and thereby caused dim and faded pictures. The question is apparent, whether the moistening liquid too will enter underneath the partially hardened sections and produce reduction of light-sensitivity. If this condition should occur, there would be no advantage of the method explained over the known methods. It must be borne in mind, that the moisture, in order to reach the unhardened parts underneath the hardened parts, must penetrate the entire non-hardened adjoining sections and then enter the latter through tiny passages. Thorough investigations have revealed that no moisture enters in practice; therefore the question is merely of theoretic interest.

Another way of treating the plate prior to the second exposure consists in washing off the unhardened parts. This may be performed in any well known manner, preferably in applying hot water to the film or plate, and thereby removing the unhardened parts.

It may be mentioned that during the washing off of the unhardened parts the hardened parts are lixiviated by the applied water, losing their sensitization. They must therefore be re-sensitized before the plate is again exposed to light.

The last described method presents the disadvantage that the half-tones are spoiled. On the other hand the complete hardening of the hardened sections is effected with certainty, which is particularly desirable, in production of black-white pictures, e. g., such as used in trick-films, silhouette-films.

The second exposure may be made either directly on the colloid layer or from the other side through the carrier, provided that the carrier is transparent. It will be readily apparent that the result will be the same and in accordance with the description in the preceding paragraphs regardless from what side

of the photosensitive body the second exposure is effected.

Broadly summarizing the invention of the copending application, mentioned previously, the method disclosed therein consists in moistening the sensitive material after exposure and in then subjecting the same to a short re-exposure without the use of a negative.

The present invention has for its object to further develop this method and to improve the same. The procedure explained above is based on the assumption that the parts hardened by the exposure do not absorb the moisture in the subsequent moistening process, while those parts which have not been struck by the light during the preceding exposure remained soft and absorb the moisture. Since the sensitivity of the colloid layer is lowered as the moisture of the same rises, the re-exposure will act strongly upon the previously hardened parts, while those parts of the colloid layer which previously were not struck by the light rays and, accordingly, remained soft will be hardened only to a slight degree due to the absorbed moisture.

It was found that the moisture applied to the material exercises a slight, yet, noticeable detrimental influence also upon the surface of the hardened parts. The detriment consists therein that the moisture enters into the hardened layer to a slight degree, thus reducing its sensitivity. A further lowering of the sensitivity is caused by the lixiviating influence upon the sensitizers due to the permeating moisture.

The fact that the gradual drying of the surfaces of the hardened parts is apt to cause spots, might be listed as an additional disadvantage.

The instant invention prevents the detriments enumerated above, by providing for quick removal of traces of moisture from the surfaces of the hardened parts. This is accomplished by adding to the moistening medium substances having low evaporating point, e. g., an alcohol or ether. There are, of course, a great many other substances suitable for this purpose.

The quick drying of the traces of moisture upon the hardened parts may also be attained by first moistening the material in the usual manner and treating the same afterwards with a solution of low evaporating temperature, which treatment might consist of washing.

There are, of course, numerous other ways for accomplishing the drying, e. g., by the use of an air current which might even be heated suitably, or by the use of heat in other suitable manner, or by mechanically drying the moisture residue, which latter manner may be realized by carrying the material over drying barrels.

All these methods effect the removal of the moisture from those colloid layers on which

the moisture should not exercise any influence. The subsequent re-exposure can, therefore, act upon the colloid parts which have been prehardened during the first exposure, 5 without any detriment and handicap.

What is considered new over the disclosure contained in the copending application, and desired to be protected by Letters Patent, is pointed out in the following claims.

10. What is claimed is:

1. Method of treating a photo-sensitive body having a colloid layer photo-sensitized with an agent adapted to harden the layer by reaction with light, consisting in exposing said body under a negative, thereby producing hardened and unhardened sections of said layer, in moistening said layer after exposure, in removing the moisture from the hardened sections of said layer, and in there- 15 after re-exposing said body to light for a short period.

2. Method of treating a photo-sensitive body having a colloid layer photo-sensitized with an agent adapted to harden the layer by 25 reaction with light, consisting in exposing said body under a negative, thereby producing hardened and unhardened sections upon said layer, in moistening said layer after exposure to make said unhardened sections in- 30 effective to the action of light rays, in removing the moisture from the hardened sections of said layer, and in thereafter re-exposing said body to light for a short period.

3. Method of treating a photo-sensitive 35 body having a colloid layer photo-sensitized with an agent adapted to harden the layer by reaction with light, consisting in exposing said body under a negative, thereby producing hardened and unhardened sections upon 40 said colloid layer, in moistening said layer after exposure to make said unhardened sections ineffective to the action of light rays, in thereafter treating said layer with a solution having low evaporating temperature to 45 remove the moisture from the surface of said hardened sections, and in thereafter re-exposing said body to light for a short period.

4. Method of treating a photo-sensitive body having a colloid layer photo-sensitized 50 with an agent adapted to harden the layer by reaction with light, consisting in exposing said body under a negative, thereby producing hardened and unhardened sections upon said colloid layer, in moistening said layer after exposure to make said unhardened sections 55 ineffective to the action of light rays, in removing the traces of moisture upon said hardened sections by the action of an air current applied to said layer, and in thereafter re-exposing said body to light for a short period without the use of a negative.

5. Method of treating a photo-sensitive body having a colloid layer photo-sensitized 60 with an agent adapted to harden the layer by reaction with light, consisting in exposing

said body under a negative, thereby producing hardened and unhardened sections upon said colloid layer, in moistening said layer after exposure to make said unhardened sections ineffective to the action of light rays, in 70 mechanically removing the traces of moisture from said hardened sections by subjecting said body to the action of suitable drying devices, and in thereafter re-exposing said body to light for a short period without the 75 use of a negative.

6. Method of treating a photo-sensitive body having a colloid layer photo-sensitized with an agent adapted to harden the layer by 80 reaction with light, consisting in exposing said body under a negative, thereby producing hardened and unhardened sections upon said colloid layer, in moistening said layer after exposure with a medium containing a substance of low evaporating temperature to 85 make said unhardened sections ineffective to the action of light rays, whereby said substance of low evaporating temperature is added to said solution in order to effect quick drying of said hardened sections after the 90 moistening process, and in thereafter re-exposing said body to light for a short period without the use of the negative.

7. Method of treating a photo-sensitive body having a colloid layer photo-sensitized 95 with an agent adapted to harden the layer by reaction with light, consisting in exposing said body under a negative, thereby producing hardened and unhardened sections upon said colloid layer, in moistening said layer 100 after exposure to make said unhardened sections ineffective to the action of light rays, in thereafter chemically removing traces of moisture from the surfaces of said hardened sections, and in thereafter re-exposing said 105 body to light for a short period without the use of said negative.

8. Method of treating a photo-sensitive body having a colloid layer photo-sensitized with an agent adapted to harden the layer by 110 reaction with light, consisting in exposing said body under a negative to produce hardened and unhardened sections upon said colloid layer, in then moistening said layer after exposure to make said unhardened sections 115 ineffective to the action of light rays, in thereafter mechanically removing traces of moisture from the surfaces of said hardened sections, and in thereafter re-exposing said body to light for a short period.

In testimony whereof I affix my signature.
CARL ROEHRICH.
